UNITED STATES PATENT OFFICE

FRANK SCOTT, OF ORBISONIA, PENNSYLVANIA

MITER MACHINE

Application filed September 19, 1931. Serial No. 563,797.

This invention relates to miter machines, and has for an object to provide a device having guides which may be set to various angles, and with a cutting implement arranged to at all times bisect the angle.

A further object of the invention is to provide a device having a bed with guides mounted to slide thereon, and a central member pivotally connected with the guides whereby said guides may be set to varying angles or in parallel relation, and with any such angle or parallel a cutting implement to bisect the angle or to cut an article at 90° relative to the parallel guides.

A further object of the invention is to provide improved means for guiding the saw, or cutting implement, relative to the guide members.

A further object of the invention is to provide improved means for clamping work against the guide members.

The invention therefore comprises a bed having a bar slideable longitudinally relative thereto, with guide members pivoted adjacent the sides of said bar and connected by means of slots with the bed whereby the movement of the bar will change the angle of the guides, said bar carrying also movable guide members for the saw or cutting implement positioning said cutting implement to accurately bisect the angle formed by the guide, and improved means for clamping work against the guides.

The drawings illustrate an embodiment of the invention, and the views therein are as follows.

Figure 1 is a view of the improved miter machine in top plan,

Figure 2 is a view of the machine in end elevation as indicated by arrow 2 at Figure 1, with a part broken out,

Figure 3 is a view in side elevation, as indicated by arrow 3 at Figure 1,

Figure 4 is an enlarged detail sectional view, taken on line 4—4 of Figure 3, and

Figure 5 is an enlarged detail sectional view, taken on line 5—5 of Figure 1 with the guide member omitted.

Like characters of reference indicate cor-

responding parts throughout the several views.

The improved miter machine, which forms the subject matter of this application, comprises a bed 10, which in ordinary construction will be an integral casting, although the invention is in no way limited to material or method of making. The bed is provided with a dove tailed slot 11 extending along the median line of said bed, with a bar 12 mounted to slide in said dove tailed slot.

At or adjacent to the opposite ends of the bar 12, spaced pairs of uprights 13—13' and 14—14' are erected. These uprights have vertically extending grooves 15, as shown more particularly at Figure 4, with blocks 16—16' slidably mounted in said grooves. Both of the pairs of uprights 13—13' and 14—14' are substantially identical, and each is provided with a cross-head 17 which is secured in any approved manner, as by the bolts or screws 18, so that the upright structure so formed is rigid with the bar 12. One or both of the blocks 16—16' is provided with a depression for receiving a spring 19 for holding the blocks 16—16' yieldingly at their upper limit for the reasons which will be hereinafter explained.

Pivoted to the bar 12 are guides 20 and 21, such pivoting being by means of screws 22 inserted in properly positioned orifices, one pair of which are shown at 23. Any number of these orifices 23 may be provided along the bar 12 so that the bar may be adjusted for differences in width of materials employed.

The guides 20 and 21 are respectively provided with slots 24 and 25, with clamping members extending through such slots, represented merely for the purpose of illustration by the winged screws 26. The blocks 16—16' are provided with guideways 27 for the receipt of a saw or other cutting implement 28. This implement, which will be called a saw generically, is provided with a back rib 29, and oppositely extending beads 30 fitting in said guideways 27. It will be noted especially from Figure 2, that the saw is wider than the length of

the guide blocks 16—16' so that the cutting edge extends below these blocks and is not affected thereby.

The bed is also provided with other grooves 31 and 32 in which are mounted bars 33 and 34. These bars slide longitudinally, and are provided with spaced recesses 35, and a pin 36 is inserted through one of said recesses 35 and into a socket 37 in the bed, shown more particularly at Figure 5. Each of these bars 34 carries an eccentric clamping member 38 which is provided with an upstanding flange 39 so that by operating one of said clamping members, work interlying said clamping member and its adjacent guide may be clamped firmly therebetween.

As shown at Figure 1, the guides 20 and 21 are set approximately at 90° relative to each other, and the saw 28 is positioned to bisect this angle forming a miter of 45°. Mitering at 45° is, of course, done in the great majority of cases, but mitering at other angles is at times necessary. To set the device to form a miter to fit any angle, the angle is first secured on a bevel, and the bevel applied to the guide members. In the case of a 45° miter, the angle will be secured by the use of an ordinary carpenter's square. The clamping screws 26 will be loosened and the bar 12 moved longitudinally until the remote sides of the guide members fit exactly to the inside of the square. The clamping members 26 are now tightened to hold these guide members in this position, and work placed between one guide member 35 and its adjacent clamping member, and clamped therein, the bar 34 being moved as necessity requires to accommodate the work. The saw, being now employed, will bisect the 90° angle and form a 45° angle. Mitering at a 45° angle is a relatively simple process, but mitering to fit an angle other than 45° is far less simple. With applicant's device, an ordinary carpenter's bevel is fitted to the angle. It is then fitted to the remote sides of the guide members 20 and 21.

Let it be assumed that it is an acute angle that is to be fitted by a miter and that the bevel, when set to fit such angle, will require the guides to be set at dot and dash line position, shown at Figure 1. Merely setting these guides to exactly correspond to the angle to be fitted will absolutely insure a fit of the miter as the saw must in all cases bisect the angle whatever it may be. It is obvious also that an obtuse angle, wherein the guides will lie between the full line positions and the dotted line positions, will be set in the same manner, and the miter will be cut with absolute fidelity. As shown in dotted lines, the guides have been set in alinement so that the saw will cut a 90° angle. By the use of this device, the accurate fitting of a miter joint to any angle is extremely simple as it is always extremely simple to obtain the exact angle on a carpenter's bevel. This being ob-

tained, and the guides 20 and 21 being set to fit this bevel, the miter cut will always be absolutely accurate. In other words, no matter what angle is represented by the various positions which may be assumed by the guides 20 and 21, the saw or cutting implement will obviously and accurately bisect the angle to form a true fitting miter. When the miter has been completed, and before the work is removed, or other work inserted, the saw is raised to its upper limit where it is held yieldingly by means of the members 19. When the work is inserted and the saw is ready for use, a tap on the top of the rib 29 will disengage it so that it will drop to position for work.

When the work to be mitered is wider than would be received with the parts arranged as shown in full lines at Figure 1, the pivot screws 22 are removed, the bar 12 moved to the left until these screws will engage some pairs of perforations as those shown at 23. The screws are again inserted, and the device is in condition to operate.

The miter machine, herein illustrated, may be modified in various ways without departing from the invention herein set forth and hereinafter claimed.

The invention is hereby claimed as follows:

1. A miter machine comprising a bed having a plurality of longitudinally extending slots, bars mounted in said slots, uprights mounted upon one of said bars and movable therewith, a cutting implement longitudinally movable through said uprights and guided thereby, guide members mounted upon the bed in convergence, the converging ends being connected with the bar carrying said uprights, means slidably connecting the guides to the bed upon opposite sides of said bar, work clamping members carried by the other bars, and means to secure said other bars at various longitudinally adjusted positions.

2. A miter machine comprising a work table having a plurality of parallel slots in its face, a bar mounted to slide in one slot, saw guides carried by said bar, bars mounted in the other slots, work guides pivoted to the first mentioned bar and extending over the second mentioned bars, means to fix the second mentioned bars in longitudinal adjustment, and clamps carried by the second mentioned bars.

3. A miter machine comprising a work table having a plurality of parallel slots in its face, a bar mounted to slide along the median line of the table in one slot, saw guides carried by said bar, bars mounted in the other slots, work guides pivoted to the first mentioned bar and extending over the second mentioned bars, means to fix the second mentioned bars in longitudinal adjustment, and clamps carried by the second mentioned bars.

4. A miter machine comprising a work table having a plurality of parallel slots in

its face, a bar mounted to slide in one slot, saw guides carried by said bar, bars upon opposite sides of the first mentioned bar mounted in the other slots, work guides piv-

eccentric clamps carried by the second mentioned bars.

In testimony whereof I have signed my name to this specification.

FRANK SCOTT. 70

5 oted to the first mentioned bar and extending over the second mentioned bars, means to fix the second mentioned bars in longitudinal adjustment, and clamps carried by the second mentioned bars.

75

10 5. A miter machine comprising a work table having a plurality of parallel slots in its face, a bar mounted to slide in one slot, saw guides carried by said bar, bars mounted in the other slots, work guides pivoted to and
15 extending upon opposite sides of the first mentioned bar and extending over the second mentioned bars, means to fix the second mentioned bars in longitudinal adjustment, and clamps carried by the second mentioned bars.

80

6. A miter machine comprising a work table having a plurality of parallel slots in its face, a bar mounted to slide in one slot, saw guides carried by said bar, bars mounted in the other slots, work guides pivoted to the first mentioned bar and extending over the second mentioned bars, means to fix the work guides to the table, means to fix the second mentioned bars in longitudinal adjustment, and clamps carried by the second mentioned bars.

85

35 7. A miter machine comprising a work table having a plurality of parallel slots in its face, a bar mounted to slide in one slot, saw guides carried by said bar, bars mounted in the other slots, work guides pivoted to the first mentioned bar and extending over the second mentioned bars, means to fix the work guides to the table at various identical angular 40 adjustments, means to fix the second mentioned bars in longitudinal adjustment, and clamps carried by the second mentioned bars.

95

45 8. A miter machine comprising a work table having a plurality of parallel slots in its face, a bar mounted to slide in one slot, saw guides carried by said bar, bars mounted in the other slots, work guides pivoted to the first mentioned bar and extending over the second mentioned bars, means to fix the second mentioned bars in longitudinal adjustment, and eccentric clamps carried by the second mentioned bars.

105

55 9. A miter machine comprising a work table having a plurality of parallel slots in its face, a bar mounted to slide along the median line of the table in one slot, saw guides carried by said bar, bars upon opposite sides of the first mentioned bar mounted in the other slots, work guides pivoted to and extending upon opposite sides of the first mentioned bar and extending over the second mentioned bars, means to fix the work guides to the table at various identical angular adjustments, means to fix the second mentioned bars in longitudinal adjustment, and
